MULTI-BLOCK-TYPE TEST TUBE HEATER

Alexander I. Newman, River Forest, Ill., assignor to
Lab-Line Instruments, Inc., Melrose Park, Ill.

Filed June 1, 1972, Ser. No. 258,933

Term of patent 14 years

Int. Cl. D24—02

U.S. Cl. D16—2 C

FIG. 1

FIG. 2

FIG. 3

FIG. 1 is a front perspective view of a multi-block-type test tube heater embodying my new design;

FIG. 2 is a rear perspective view thereof;

FIG. 3 is a bottom view thereof.

I claim:

The ornamental design for a multi-block-type test tube heater, as shown and described.
